UNITED STATES PATENT OFFICE.

WILLIAM H. HONSBERGER, OF BUFFALO, NEW YORK.

VALVE.

SPECIFICATION forming part of Letters Patent No. 759,277, dated May 10, 1904.

Application filed December 23, 1903. Serial No. 186,317. (No model.)

To all whom it may concern:

Be it known that I, WILLIAM H. HONSBERGER, of Buffalo, New York, have invented certain new and useful Improvements in Valves, 5 of which the following is a full, clear, and exact description.

My invention relates to valves, and more particularly to a valve wherein one inlet is closed and a second passage put in connection 10 with the outlet by pressure supplied through a secondary or emergency inlet.

My invention while of wider utility is especially adaptable to an emergency-air system as applied to air-brakes, and without limiting 15 myself to that particular use I shall describe the same as used in that connection.

Referring to the drawing herewith, 1 is the body or casing of the valve.

2 is the main cylindrical boring, and 3 is a 20 float-valve.

4 is a cone-shaped crown to the valve 3, and 5 is a similarly-shaped recess at the top of the cylindrical opening 3 to receive the crown 4 when the valve 3 is forced upward.

25 6 is the regular air-inlet, and 7 is the air-outlet. The inlet 6 connects with the tank or air-supply, and 7 connects with the brake-cylinder.

8 is an emergency-air inlet, having an enlarged opening 9 through the nut 10.

11 and 12 constitute a by-pass connecting the main chamber 2 with the outlet 7 when the valve 3 is raised to the point when its face is on the broken line.

35 I will now describe the operation of my invention. Under ordinary circumstances the air passes from the inlet 6 to the main chamber 2 and thence to the outlet 7. In case of an emergency—as, for example, in case of a

40 break in the pipe leading to the inlet 6, or the failure of the regular air-pressure—the emergency air is turned on into the opening 8. This pressure applied to substantially the entire base of the valve 3 in the area 9 forces

45 the valve 3 upward and seats its crown 4 in the space 5. The base of the valve 3 is then above the opening 11, and the emergency air passes out through the passages 11 and 12 to the outlet 7 and thence to the brake-cylinder. In

50 this movement of the valve 3 the inlet 6 is

closed and held closed so long as air is admitted through the opening 8. When the demand for the emergency air is past and it is desired to use air from the inlet 6, if the valve 3 has not fallen by gravity in the meantime 55 the pressure of the air upon the crown 4 will drive it down and re-establish the connections in the regular manner. The employment of the inlet 6, opening upon the cone-shaped crown, is of great importance. It is not safe 60 to rely upon gravity to reseat the valve, and positive means must be used to overcome any tendency to stick or bind.

Having thus described my invention and its method of operation as applied to one specific 65 use, what I claim is—

1. A valve comprising a main cylindrical chamber and a reduced end to said chamber, a cylindrical float-valve fitting therein and having a crown to fit into said reduced end, a main 70 inlet connecting with said chamber and opening into said reduced end, an outlet open to said chamber when said valve is in its normal position, a second inlet entering said chamber underneath said valve, and a by-pass from said main chamber to said outlet, closed by said valve when in its normal position and opened when said valve is raised, substantially as and for the purposes set forth.

2. In a valve, a main chamber, a cylindrical 80 float-valve traveling in said chamber, a main inlet-opening over the crown of said float-valve, an auxiliary inlet-opening under said float-valve, a main outlet leading from said main chamber, and a by-pass leading from said main chamber to said main outlet, whereby pressure from the main inlet seats said valve in position to close said by-pass and open said main outlet, and pressure from the auxiliary inlet seats said float to close said main inlet 85 and said main outlet and to open said auxiliary inlet and said by-pass, substantially as and for the purposes set forth.

In witness whereof I have hereunto set my hand in the presence of two witnesses.

WILLIAM H. HONSBERGER.
